UNITED STATES PATENT OFFICE.

HENRY E. REEVE, OF NEW YORK, N. Y.

FUEL-REGULATOR.

14,894.

Specification of Reissued Letters Patent. Reissued June 22, 1920.

Original No. 1,238,940, dated September 4, 1917, Serial No. 747,648, filed February 11, 1913. Application for reissue filed March 1, 1920. Serial No. 362,554.

DIVISION A.

To all whom it may concern:

Be it known that I, HENRY E. REEVE, a citizen of the United States of America, and residing at New York, in the county of Kings and State of New York, have invented new and useful Improvements in Fuel-Regulators, of which the following is a specification.

My invention relates particularly to 10 thermostatic control of the gas supply for water heaters.

The object of the invention is to provide a sensitive and yet positive automatic control of the gas supply in what are commonly 15 termed "automatic heaters."

My invention embodies in part a thermostatic device which acts in accordance with the temperature of the heater to control flow of fluid under pressure to a pressure 20 actuated device and which device in turn operates certain valve mechanism to positively control the flow of gas to the burner. A special feature resides in the utilization of the gas, as the fluid under pressure for 25 operating the pressure operated device. Of importance in this connection, I preferably provide a means for automatically releasing the pressure upon the pressure actuated device when the flow of actuating fluid there- 30 to has been cut off.

Another feature of importance is the provision of means for cutting off flow of gas to the main burner in the event of the pilot becoming ineffective. Mechanism operated 35 directly from a thermostat for automatically and positively cutting off flow of gas to the burner in the event of the heater becoming excessively hot or "overheating" is also a feature of this invention.

Various other features will appear as the specification proceeds.

The accompanying drawings illustrate the invention in several of its preferred forms, but I would have it understood that 45 various other changes and modifications may be made therein without departing from the true scope of the invention.

Figure 1, is a vertical sectional view of a preferred embodiment of the invention, 50 parts being broken away.

Fig. 2, is a plan view of the lever member which carries the auxiliary gas valve and is operated by the thermostat.

Fig. 3, is a view similar to Fig. 1, of a somewhat modified form of the invention. 55

Fig. 4, is a plan view of the lever member illustrated in Fig. 3.

Fig. 5, is a horizontal sectional view taken substantially on the line 5—5 of Fig. 3, illustrating the gas-tight joint and the 60 pivot mounting for the lever which operates the main valve.

Fig. 6, is a sectional view taken on a plane at right angles to that of Fig. 5 and substantially on the line 6—6 of Fig. 5. 65

Fig. 7, is a detail perspective view showing the various parts of the preferred form of gas valve.

Fig. 8, is a similar view of these parts as assembled. 70

Fig. 9, is a horizontal sectional view of the thermostat shown in Fig. 3, this view being taken substantially on the line 9—9 of that figure.

Fig. 10, is another sectional view of the 75 same taken substantially on the line 10—10 of Fig. 3, and

Fig. 11, is still another such view taken substantially on the line 11—11 of Fig. 3.

A portion of the water chamber or reservoir of the heater is indicated at 15. 16 designates the gas supply pipe or conduit which supplies gas to the apparatus, and 17 is the conduit which conveys gas from the controlling apparatus to the main burner. 80

The flow of gas to the main burner may be controlled directly by a main regulating valve 18 and a pressure operated device is preferably utilized as the means for positively operating this valve. The pressure 90 operated device is here shown in the form of a diaphragm 19 mounted within a diaphragm chamber 20 and mechanically connected with the valve by means of a post 21 on the diaphragm which engages with 95 one end of a pivoted lever 22 whose opposite end is connected with the valve. To properly regulate the rising and falling movement of the diaphragm with the closing and opening movement of the regulating valve, 100 these parts, or the mechanical connections between are preferably made relatively adjustable. Such adjustment is in this case provided for by connecting the end of the lever adjustably to the diaphragm post, as 105 by engaging it between the adjustable abut-

ments 23, carried by the post (see Fig. 1). Also the connection between the diaphragm and valve is preferably made a more or less yielding one to permit a slight further 5 movement of the diaphragm after the valve has been seated, so as to thereby hold the valve all the more firmly seated. The lever 22 is for this purpose, shown in Fig. 1, as provided with a spring end portion 24 which 10 will yield to permit further upward movement of the diaphragm after the valve has been engaged with its seat 25.

While the pressure actuated device may be operated by any suitable fluid under 15 pressure, I prefer to use the gas itself as the medium for operating the device. An auxiliary gas passage 26 is therefore preferably provided leading to the underside of the diaphragm, and flow of the actuating 20 fluid is governed by an auxiliary gas valve 27 arranged to coöperate with the seat 28 at the end of such passage. Means is also provided to permit the escape of gas from chamber 20, as will be referred to later.

25 A thermostatic device of some sort is provided for controlling operation of the pressure actuated device. In the first figure the thermostatic device is shown as consisting simply of a tube 29 extending up into the 30 reservoir and having the rod 30 or like connection secured to the upper end thereof. The tube being made of brass or other material possessing a relatively high coefficient of expansion, it will be clear that as 35 the water in the reservoir becomes heated the tube will, since it is anchored at its lower end at 31, expand upwardly and lift the connection 30, while upon cooling of the water the tube will contract and lower 40 the connection 30. The so-called auxiliary valve 27 which governs admission of the actuating fluid to the pressure operated device is mounted in any suitable way and it is here shown as carried on the end of 45 an arm or lever 32 to the opposite end of which lever the thermostat rod is connected by a metallic tape or ribbon 33. The operating arm 32 is pivoted so as to be capable of the oscillatory movement necessary in the 50 opening and closing of the auxiliary gas valve, and to reduce friction as much as possible and to eliminate lost motion I prefer to use a special form of pivot mounting at this point. This mounting consists of 55 a roller 34 carrying the valve operating arm and making rolling engagement with a relatively fixed support 35, and a pair of flexible metallic tapes or ribbons, which pass in opposite directions each part way around 60 the roller. The ends of these ribbons are fastened either directly or indirectly to the roller, so that the roller may be rotated thereby. In the form shown in Fig. 1, the ribbon 33 which comes from the thermostat 65 extends downwardly part way around the

roller and is secured in respect to the roller by having its end engaged over a pin 36 on the lever 32 and another ribbon 37, passes upwardly at the opposite side of the roller and part way therearound to where it is secured in respect to the roller by being engaged with the pin 38. The roller and lever are made fixed in respect to each other, so it will be clear that the anchoring of the ribbons to the lever is the equivalent of 70 fastening them direct to the roller. In Fig. 3 the ribbons are in fact shown secured to the roller at points 39 and 40. The second ribbon has its opposite end secured to the roller support, as indicated at 41. When 80 made as in Fig. 1, I have provided guides 42 for holding the ribbons in proper engagement with the surface of the roller. The roller is in some way held in proper engagement with its support 35 and provision is 85 made for rotating it in a direction reverse to that in which it is turned by the thermostat. In Fig. 1, a spring 43 is shown for holding the roller in proper engagement with its support and a second spring 44 is 90 illustrated which acts upon the lever in opposition to the turning movement of the thermostat. In the form disclosed in Fig. 3, a single spring 45 performs both these functions, it being, as shown, connected 95 with the lever so as both to lift the lever in opposition to the pull of the thermostat and to draw the lever over with the roller in engagement with the support. To prevent side slipping of the roller with respect 100 to the support the roller may have flanges as indicated at 46 in Figs. 3 and 4 to engage over the sides of the support, or the place of these flanges may be taken, as shown in Figs. 1 and 2, by making up the lever with 105 two side bars 47 to fit the opposite sides of the support. The lever shown in Figs. 3 and 4 also is preferably made up of two side bars 48 to pass on opposite sides of the support, but in this case the side bars 110 do not contact with the support. Preferably also the valve lever has a more or less flexible end portion 49 which acts to hold the valve closed under a certain amount of 115 spring tension.

To secure the proper coöoperative action between the thermostat and the auxiliary valve, a certain amount of adjustment in the relation of these two parts may be necessary. This I provide for preferably by 120 mounting the support so that it may be shifted to carry the valve on the valve lever 32 toward or away from its seat. Thus in Fig. 1 the support is made with rounded ends 50 guided in sockets 51, the actual 125 shifting being accomplished by an adjusting nut 52 on the outer threaded end 53 of the support. In the form shown in Figs. 3 and 4 the support has rounded ends 130 guided in sockets as before, but the shifting 135

means in this instance consists of the screws 54 and 55 engaging with the upper and lower ends respectively of the support. The support may be held against rotative movement in any suitable way, such for instance, as by providing it with an outstanding arm 56 slidingly engaged over a fixed guide stud 57.

The operation of the parts thus far described will be best understood by reference to Fig. 1. Normally with the burner in operation, the flow of gas is from the supply pipe 16 through a passage formed by the gas chamber 58, connection 59 and valve chamber 60, to the main regulating valve and through conduit 17 to the burner. The thermostat, being subjected to the heat of the water in the reservoir, expands, thereby pulling upwardly on the ribbon 33 and 15 rotating the roller and its attached lever, until finally at the predetermined temperature for which the thermostat has been set, the auxiliary valve 27 is carried away from its seat. Gas under pressure now flows 20 through the auxiliary gas passage to the underside of the diaphragm. The diaphragm is lifted by this pressure of gas and thereupon acts to rock the lever 22 to close the main regulating valve. Further feed 25 of gas to the burner is thus cut off. As the hot water is consumed or becomes cooled, the thermostat contracts, thereby releasing its upward pull on the ribbon 33 and the spring 44 acting in opposition to this pull 30 then operates to close the auxiliary valve 27. This condition of the parts is represented in Fig. 1. Further supply of gas to the underside of the diaphragm is thus cut off and the slight leakage of gas causes a 35 slight reduction in the pressure beneath the diaphragm. This reduction in pressure and the weight of the diaphragm itself tend to cause the diaphragm to descend. I preferably utilize this slight preliminary descending movement to operate certain mechanism for accelerating the movement of the parts. This accelerating mechanism is here shown in the form of a relief valve 61 carried on the diaphragm and arranged to normally 40 close a relief opening 62 therein. This valve may be supported by a lever 63, pivoted at 64 on the diaphragm. The escape of gas from chamber 20 is normally through the opening 62 past the valve 61. The ordinary mechanical construction of the parts affords sufficient leakage past this valve to start the descent of the diaphragm, but it should be understood that the leakage may be permitted to take place in any other suitable manner. At the time of the first preliminary descending movement of the diaphragm, the valve carrying arm is temporarily supported so that the diaphragm will fall away from the valve and thus open up 45 the relief port 62. The means for thus tem-

porarily sustaining the valve is in Fig. 1 a series of spring fingers 65, which engage frictionally with a knob 66, on the stud 67 carried by lever 63. The frictional engagement between these parts is sufficient to support the relief valve while the diaphragm is slowly settling, and the relief valve being thus held open, the gas beneath the diaphragm is allowed to suddenly escape. This escape of the gas permits the diaphragm to fall quickly and as it falls, it rocks the valve lever 22 downward and again opens the regulating valve for the main burner. The small amount of gas released from beneath the diaphragm may be allowed to escape to 75 atmosphere or be otherwise disposed of through a vent 68. By adjusting the support for the valve carrying lever the amount of expansion in the thermostat necessary to open the auxiliary gas valve and hence the 80 temperature at which the main burner will be cut off, may be determined at will. For convenience in setting the parts for different temperatures there may be provided a scale 85 69, laid off in degrees of temperature. 90

To provide against overheating, the thermostat is preferably made to itself directly cut off flow of gas upon excessive heating. This may be conveniently accomplished by mounting a cut-off valve 70 on the valve lever 95 32 to coöperate with a valve seat 71 at the point where the gas supply pipe 16 opens into the gas chamber 15. If the heater should become excessively hot, as for instance, by reason of the pressure operated device failing to properly cut off flow to the main burner, then, the thermostat in expanding still further will turn the lever 32 and carry the valve 70 into engagement with its seat, thereby positively cutting off any 105 further flow of gas to the burner. The seat for the auxiliary valve and the seat for the cut-off valve are disposed substantially opposite to each other, so that the valve lever may vibrate therebetween to carry either 110 one or the other valve to its seat. The parts are so proportioned and so disposed that only upon excessive heating will the lever be shifted far enough to close the cut-off valve.

As a further safeguard, means are preferably provided for shutting off flow to the main burner in the event of the extinguishment of the pilot. A means for this purpose is disclosed in Fig. 1, wherein 72 designates the pilot for the main burner, and 73 a branch conduit for supplying it with gas. Associated with this pilot and subject to the heat thereof is a thermostatic device 74 carrying a valve 75, which is arranged to engage a seat 76, and serves to 120 control flow through a conduit 77 leading to the pressure operated device. The thermostatic device, which may be of the usual compound construction, is heated by the pilot so long as it is burning and in its ex- 125

1 panded condition it serves to hold the valve 75 closed. When however the pilot is extinguished this thermostatic device cools off and lifts valve 75 from its seat. A flow of 5 gas is now opened up from branch conduit 73 through the pilot casing 78, past the now open valve 75 and conduit 77 to the pressure actuated device which operates in the manner previously described to shut off 10 flow to the main burner.

In Figs. 3 and 4 the apparatus is materially simplified by leaving out the pilot control of the main burner and the overheating protective device. In this case the gas 15 simply flows from the supply conduit 16 direct through the valve chamber 60 to the conduit 17 leading to the burner and the gas for operating the diaphragm is taken off from the supply conduit through a 20 branch conduit 79 which extends to the gas chamber 58 within which is located the auxiliary valve which controls flow to the diaphragm. The thermostat illustrated in this view and in detail in Figs. 9, 10 and 11 is 25 extremely sensitive to change in temperature. It is made substantially as follows:—

A tube 80 for instance of brass, open at the bottom is secured at the bottom to a wall of the water reservoir. The upper end 30 of this tube is closed by a plug 81 to which is secured the upper end of a rod 82 for instance of steel. The lower end of this rod carries a sleeve 83. A tubular or semi-tubular member 84 for instance of zinc, is 35 secured to the sleeve 83 at its lower end, and at its upper end carries a second sleeve 85. This sleeve 85 is not attached to the tube 80 and has a free passage for the rod 82. The rod 86 for instance of steel, is 40 secured to the sleeve 85 and passes freely through the sleeve 83 at the bottom. The zinc tube 84 has a high co-efficient of expansion and being in contact with the inner wall of the brass tube 80 receives by 45 conduction through the tube, the heat of the water in the water container. As the temperature of the water rises, the tube 80 is elongated and carries with it the rod 82 and sleeve 83 and zinc tube 84 and the 50 latter in turn is itself elongated giving an additional pulling movement to the sleeve 85 and the rod 86. The rod 82 and rod 86 are preferably of relatively non-expansive material and it will also be noted that 55 they are so spaced apart throughout the principal part of their ranges from the tubes that they are but little affected by changes of temperature and therefore but little, if any, detract from the effective 60 movement of the brass and zinc tubes. The rod 86 may be connected to the tape 33 which operates the roller by means of a suitable coupling 87.

To insure the valves always seating properly they are preferably each mounted on

a universal joint so that they may automatically adjust themselves to their respective seats. The preferred form of such joint is illustrated in detail in Figs. 7 and 8. In these views the main regulating valve 18 is 70 shown provided with a partially spherical recess 88, on the back thereof into which fits a correspondingly spherical head 89 on the bearing member 90. This bearing member is suitably attached to the element 75 which supports the valve which in the case described is the valve operating lever 22. The usual method of attachment is to pass the stem 91 of the bearing member into an 80 opening in the supporting member and rivet 85 it therein as indicated at 92, Fig. 1. The head of the bearing member is by suitable means held in engagement with the spherical recess in the back of the valve—such means being illustrated as a coil spring 93 85 having one of its arms 94 secured in the body of the valve and its other arm 95 engaging the bearing member as by passing freely through an opening 96 therein. The valve plate is thus supported so that it may 90 move freely in all directions to a limited extent, as a result of which it will adjust itself automatically to always make firm engagement with its valve seat. All of the 95 valves are preferably mounted in this same way. A firm and secure seating of the valves is further facilitated by making the valve seat in the form of an upstanding annular ridge 97 as shown in the case of the auxiliary valve 27 in Fig. 1. The same 100 form of universal mounting which is used for the valves may also be employed in connecting the stud of the temporary supporting device to the lever which carries the pressure releasing valve of the diaphragm. Thus as shown in Fig. 1 the stud 10 may be made with a rounded head 98 for engagement with a spherical recess 99 in the valve carrying lever 63. The stud thus forms a bearing member similar in function to the bearing member of the valves, and the rounded head of this member may be held in engagement with the recess by a spring 93, the same as in the case of the 105 valves.

To prevent leakage at the joint where the valve operating lever 22 passes into the valve chamber 60 of the main regulating valve, I have devised a special form of gas tight joint, shown in detail in Figs. 5 and 6 and consisting in substance of a flexible diaphragm connected between the lever and the wall through which the lever passes. This diaphragm is preferably made up of two thin metallic disks 100 and 101 interconnected at their edges and connected at their central portions to the lever and the supporting wall respectively. The disk 100 is joined to the lever preferably by securing it to a bushing 102 fast on the lever and the

disk 101 is preferably connected to a bushing 103 mounted in the supporting wall. The opening 104 through which the lever passes is, it will be noted, of a size sufficient 5 to permit free movement of the lever. The lever is in this way pivotally supported in a manner which is substantially frictionless. To prevent sidewise movement of the lever and to limit its pivoting movement to 10 a single plane—that is to a straight up and down rocking movement, I preferably provide guiding means in the form of a horizontally disposed yoke 105 engaged at its center with the lever and having pivots 106 15 at its opposite ends engaged in suitable bearings 107. This yoke may, as shown, be connected to or form a part of the bushing 102. The pivots of the yoke are preferably disposed in the same plane with the diaphragm 20 so as to substantially coincide with the line of flexure of the diaphragm, the yoke being for this purpose off-set as indicated at 108 to bring the pivots into this plane.

A slight variation in the manner of temporarily supporting and opening the pressure releasing diaphragm valve is indicated in Figs. 3 and 4. In this case the relation of the parts is reversed, the spring fingers 109 being connected to the valve and the 25 catch member 110 for engagement with these fingers being supported apart from the valve. Such support is shown as an adjustable sleeve 111. In this case the valve carrying lever 63 is dispensed with, the pressure releasing valve, here designated 112, being simply provided with a spindle 113 30 guided in a yoke 114 and carrying the spring fingers on its upper end. In this form when flow to the diaphragm is shut off 40 and the diaphragm begins to descend it moves away from the diaphragm valve 112 which is frictionally held by the spring fingers 109 engaging the catch member 110. This opens the relief port and allows a 45 quick escape of the gas from beneath the diaphragm so that its movement and the movement of the main regulating valve is accelerated. As the diaphragm carries the yoke 114 downward with it, the yoke 50 engages the diaphragm valve and pulls it and the spring fingers downward away from engagement with the catch member so that the valve 112 again closes the relief port. Since the normal pressure of gas is only 55 slightly above atmospheric pressure, the weight of the valve 112 and attached parts is sufficient to keep it closed normally.

Suitable means may be provided for manually cutting off the flow of gas to the apparatus. Such means is here illustrated in the form of the hand valve 115.

The thermostatic device of Fig. 3 and the mechanism for transmitting the effect of the thermostatic element to the valve 27 is

claimed in my concurrent reissue application No. 362,555.

I claim:

1. In a water heater, a reservoir, a main gas burner for heating the same, pressure actuated means controlling said main burner, thermostatic means subjected to the heat of the reservoir for controlling flow of gas to the main burner, a pilot for the main burner and thermostatic means subjected to the heat of the pilot for controlling flow of actuating fluid to the pressure actuated means which controls the main burner. 70

2. In a heater regulating system, the combination with the reservoir and a suitable gas burner for heating the same, of a main 80 gas regulating valve, a gas operated diaphragm, a mechanical connection between said diaphragm and said valve, a valve in said diaphragm, a gas supply passage leading to the opposite side of said diaphragm, 85 an auxiliary gas valve for said passage and heat controlled means for operating said auxiliary gas valve.

3. In a heater regulating system, a reservoir and a suitable gas burner for heating 90 the same, means controlling flow of gas to the burner, a pressure operated device controlling the burner controlling means and arranged when actuated by fluid under pressure to cut off flow of gas to the burner, a 95 thermostatic device controlling flow of fluid under pressure to the pressure operated device and arranged in one position to cut off flow of actuating fluid to said device and means adapted to release the pressure upon 100 the pressure operated device when the flow of actuating fluid thereto is thus cut off.

4. In a gas regulating device, a main gas valve, a diaphragm mechanically connected with said valve and having a gas passage 105 therein, a valve for said passage at one side of said diaphragm and carried by said diaphragm and a heat operated auxiliary valve for controlling the flow of gas to the opposite side of said diaphragm. 110

5. In a gas regulating device, a main gas valve, a diaphragm mechanically connected with said valve and having a gas passage therein, a valve for said passage carried by said diaphragm, a heat operated auxiliary 115 valve for controlling the flow of gas to said diaphragm and means for engaging said diaphragm valve to hold it and permit said diaphragm to descend a certain distance independently of such valve. 120

6. In a gas regulating device, a main gas valve, a diaphragm mechanically connected with said valve and having a gas passage therein, a valve for said passage carried by said diaphragm, a heat operated auxiliary 125 valve for controlling the flow of gas to said diaphragm, means for engaging said diaphragm valve to hold it and permit said

- diaphragm to descend a certain distance independently of such valve and means for disengaging said diaphragm valve in the latter part of the downward movement of 5 the diaphragm.
7. In a water heater, a reservoir, a main gas burner for heating the same, gas actuated means controlling said main burner, thermostatic means subjected to the temperature of the water in the reservoir for controlling the said gas actuated means, a pilot for the main burner and thermostatic means subjected to the heat of the pilot for controlling the flow of gas to the gas 10 actuated means which controls the main burner.
8. In a water heater, a reservoir, a gas burner for heating the same, gas actuated means controlling said gas burner and having a leakage, thermostatic means subjected 20 to the temperature of the reservoir for controlling flow of gas to said gas burner, a pilot for said gas burner and thermostatic means subjected to the heat of the pilot for controlling flow of gas to the gas actuated 25 means which controls said gas burner.
9. The combination of a water storage reservoir, a main heating burner, a pilot burner, a main valve controlling the flow 30 of fuel to the main burner, a gas pressure operated device for operating said valve, means for operating said gas pressure device when the pilot burner becomes ineffective including a thermostatic device controlled by said pilot burner, a thermostatic device controlled by the temperature of water in said reservoir and means controlled thereby for operating said gas pressure operated device.
- 40 10. The combination of a water storage reservoir, a main burner, a pilot burner, a valve controlling the flow of fuel to the main burner, a fluid pressure operated diaphragm for moving said valve, a thermostatic device influenced by the temperature of water in said reservoir, means controlled thereby for operating said diaphragm, a thermostatic device responding to the heat from said pilot burner and means controlled 45 thereby for operating said diaphragm.
- 50 11. The combination of a water storage reservoir, a burner, a pilot, a main valve controlling the flow of fuel to the burner, a fluid pressure operated diaphragm for moving said valve, a thermostatic device influenced by the temperature of water in said reservoir, means controlled thereby for operating said diaphragm, a thermostatic device responding to the heat from said 55 pilot, means controlled thereby for operating said diaphragm, and means controlled from said main thermostatic device for discontinuing the supply of gas to the burner in case of the development of excessive 60 temperature in the reservoir.
- 65 12. In combination, a water storage reservoir, a gas burner for heating the water in the reservoir, a conduit for supplying gas to said burner, a main valve therefor operated by gas pressure, a main thermostatic device having one end in said water storage reservoir, a housing for the other end of said device, a valve seat in said housing having a passage, an auxiliary valve connected to said thermostatic device for co-acting with said seat to open and close the passage therethrough and thereby open said main gas valve when the water gets cold and close it when the water gets hot, a pilot, a thermostatic device affected by said pilot, and means controlled by said pilot thermostatic device for closing the main gas valve when the pilot becomes ineffective. 70
- 75 13. In a heater regulating system, a water reservoir and a suitable main gas burner for heating the same, means controlling flow of gas to the main burner, a pressure actuated device for operating said controlling means, a pilot for the main burner and means adapted upon extinguishment of the pilot to 80 admit fluid under pressure to the pressure actuated device whereby to cause said device to operate the controlling means to cut off flow of gas to the main burner.
- 85 14. In a heater regulating system, a water reservoir and a suitable main gas burner for heating the same, means controlling flow of gas to the main burner, a pressure actuated device for operating the controlling means arranged upon admission of fluid under 90 pressure thereto to operate the controlling means to cut off flow of gas to the main burner, a thermostatic device heated by the reservoir, means operated by the thermostatic device when heated to admit fluid under 95 pressure to the pressure actuated device, a pilot for the main burner and a thermostatic device heated by the pilot, adapted upon extinguishment of the pilot to 100 admit fluid under pressure to the pressure actuated device.
- 105 15. In a heater regulating system, a water reservoir and a suitable main burner for heating the same, a main regulating valve controlling flow of gas to the burner, a diaphragm operatively connected to the main valve, an auxiliary valve controlling flow of gas to the diaphragm for operating the same, a thermostatic device subjected to the heat of the reservoir, connected with the 110 auxiliary valve and adapted on a rise in temperature to open the auxiliary valve to admit gas to the diaphragm, a pilot for the main burner, a gas passage leading to the diaphragm and a thermostatic device subjected to the heat of the pilot, adapted when heated thereby to cut off flow through such passage and when cooled to open up flow through said passage. 115
- 120 16. In a device of the character set forth, 125

the combination with a suitable gas burner, of a main regulating valve controlling said burner, a gas pressure operated device connected with said valve for operating the same, an auxiliary gas passage leading to said pressure operated device, a main gas passage leading to the main regulating valve, a thermostatic device and valve mechanism controlled by the thermostatic device 10 for governing flow through the auxiliary gas passage and main gas passage.

17. In a device of the character set forth, the combination of a gas burner, a main regulating valve controlling said burner, a gas pressure operated device connected with said valve for operating the same, an auxiliary gas passage for supplying gas under pressure to the pressure operated device, a main gas passage leading to the main regulating valve, valve mechanism controlling flow through the auxiliary gas passage and through the main gas passage, and a thermostatic device connected with the said valve mechanism adapted under the influence of heat to first open up flow through the auxiliary gas passage and thereafter to decrease flow through the main gas passage.

18. In a device of the character set forth, the combination of a gas burner, a main regulating valve controlling said burner, a gas pressure operated device connected with the regulating valve for controlling the same, a gas chamber, a gas supply conduit opening into said chamber, an auxiliary gas passage extending from the interior of said chamber to the pressure operated device and disposed substantially opposite to the opening of the supply conduit thereinto, a lever pivoted in the gas chamber, oppositely seating valves mounted on one end of the said lever and arranged to control the main and auxiliary gas passages respectively and a thermostatic device connected with the opposite end of the lever for operating the same.

19. In combination, a water storage reservoir, a gas burner for heating the water therein, a conduit for supplying gas to said burner, a main valve therefor operated in one direction by gas pressure, a main thermostatic device having one end in said water storage reservoir, a housing for the other end of said device, a valve seat in said housing having a passage, a valve connected 50 to said thermostatic device for coacting with said seat to open and close the passage therethrough and thereby open said main gas valve when the water gets cold and close it when the water gets hot, a pilot, a thermostatic device affected by said pilot, means controlled by said pilot thermostatic device for closing the main gas valve when the pilot becomes ineffective, and means controlled by one of the thermostatic devices for discontinuing the supply of gas to said gas

burner in case of excessive temperature development.

20. In a device of the character set forth, the combination with a suitable burner, of a main regulating valve therefor, a pressure operated device connected with the main regulating valve for operating the same, a thermostatic device, means operated by said thermostatic device to control flow of fluid under pressure to the pressure operated device, whereby to control the burner through the medium of the pressure operated device and means operated by the thermostatic device adapted under excessive heat conditions to cut off flow of gas to the burner, whereby the thermostatic device will upon excessive heating act directly to reduce flow of gas to the burner independently of the control exercised by the pressure operated device.

21. In a device of the character set forth having a chamber, a diaphragm forming a wall thereof and provided with a valve passage, a valve carried by the diaphragm and controlling said passage, means for controlling the admission of fluid under pressure to the diaphragm chamber, whereby to cause movement of the diaphragm in one direction, spring fingers engaging the valve to temporarily hold the same while the diaphragm is moving in the opposite direction, and means operated by said diaphragm.

22. In a device of the character set forth having a chamber, the combination of a diaphragm forming a wall thereof and provided with a valve passage, a lever pivoted on the diaphragm, a valve carried by said lever and controlling the passage in the diaphragm, means for controlling the admission of fluid under pressure to the diaphragm chamber to cause movement of the diaphragm in one direction, spring fingers arranged to temporarily hold the lever whereby to hold the valve open when the diaphragm is moving in the opposite direction and means operated by said diaphragm.

23. In a device of the character described having a chamber, the combination of a diaphragm forming a wall thereof, means for controlling the admission of fluid under pressure to said diaphragm chamber, means operable by said diaphragm, a valve for controlling the flow of gas from one side of the diaphragm to the other and means for opening the valve when the diaphragm starts to collapse, said means including a plurality of spring fingers for retarding movement of said valve.

24. In a device of the character described having a chamber, the combination of a diaphragm forming a wall thereof, means for controlling the admission of fluid under pressure to said diaphragm chamber, means operable by said diaphragm, a valve for controlling passage of gas from one side of the

diaphragm to the other and means for causing a sudden opening movement of the valve when the diaphragm starts to collapse, said means including a spherically surfaced member and a plurality of spring fingers for engaging the same.

25. In a device of the character described having a chamber, the combination of a diaphragm forming a wall thereof, means for controlling the admission of fluid under pressure to said diaphragm chamber, means operable by said diaphragm, a valve controlling the passage of gas from one side of said diaphragm to the other, and means for automatically opening the valve when the diaphragm begins to collapse.

26. In a water heater, a main burner, a main regulating valve controlling the flow of gas to the main burner, a diaphragm operatively connected to said valve, an auxiliary valve controlling the flow of gas to the diaphragm, a thermostat subjected to the heat of the water and operatively connected with the auxiliary valve, a pilot for the main burner having a gas passage leading to said diaphragm and a thermostatic device controlled by the operation of the pilot for controlling the flow of gas through said passage to said diaphragm for operating the diaphragm to shut off the main valve upon extinguishment of the pilot.

27. In an apparatus of the character described having a chamber, the combination of a main gas valve, a diaphragm forming a wall of the chamber and mechanically connected to said valve for operating the same, a valve controlling the flow of gas from one side of the diaphragm to the other, said latter valve being operated by the movement of said diaphragm, means for engaging said latter valve to hold it and permit the diaphragm to collapse a certain amount independently of the valve and a heat operated auxiliary valve for controlling the flow of gas to said diaphragm.

28. The combination in a water heater of a main gas regulating valve, a diaphragm operatively connected to said valve and operated by gas pressure, a valve operated by the movement of the diaphragm for controlling the flow of gas from one side of the diaphragm to the other, an auxiliary valve controlling the flow of gas to the pressure side of said diaphragm and a heat operated device for operating said auxiliary valve.

29. In a water heater, a reservoir, a gas supply pipe leading to a burner for heating the water in said reservoir, a main valve for controlling the flow of gas to said supply pipe to said burner, a gas pressure operated diaphragm connected to said main valve, a main thermostatic device responding to the changes in temperature of the water in said reservoir, means controlled thereby for controlling the pressure of gas on said

diaphragm, a pilot, a pilot thermostatic device responding to the temperature of the pilot, and means controlled by said pilot thermostatic device for controlling the pressure of gas on said diaphragm.

30. In a water heater, a reservoir, a main gas valve, a gas pressure operated device for moving said valve, a pilot burner, two independent valves for modifying the gas pressure on said device, two thermostatic devices for operating said two valves respectively, one responding to the temperature of the water in said reservoir and the other responding to the heat of the pilot burner.

31. In a heater, a reservoir, a main gas valve, a gas operated device for moving said valve including a diaphragm having a passage for the movement of gas at all times, a pilot burner, two valves for modifying the gas pressure on said device, two thermostatic devices for operating said two valves respectively, one responding to the temperature in said reservoir and the other responding to the heat of the pilot burner.

32. In a heater, a reservoir, a main gas valve, a gas operated device for moving said valve including a diaphragm having a passage for the movement of gas at all times, a valve for partially closing said passage, a pilot burner, two valves for modifying the gas pressure on said device, and two thermostatic devices for operating said two valves respectively, one responding to the temperature in said reservoir and the other responding to the heat of the pilot burner.

33. In a water heater, a main gas valve, a cut off valve, a thermostatic device for closing the cut off valve when the temperature of the heater exceeds a certain limit, gas pressure operated means controlled by the thermostatic device for opening and closing the main gas valve, a pilot burner, and means responding to the heat of the pilot burner for operating the means for opening and closing the main gas valve.

34. A reservoir, a gas burner for heating the same, a gas pressure actuated means including a diaphragm controlling said gas burner and provided with means for permitting a leakage, a thermostatic means subjected to the temperature of the reservoir for controlling the flow of gas to said burner, a pilot for said burner and a thermostat subjected to the heat of the pilot for controlling the flow of gas to the pressure actuated means which controls said burner.

35. A water storage reservoir, a gas burner for heating same, a main gas valve for controlling flow of gas to said burner, a casing, a diaphragm therein connected to said main valve, a thermostat in the reservoir for controlling pressure of gas on said diaphragm, said diaphragm and casing having means for the escape of gas, a pilot and

- a thermostat affected thereby for controlling the pressure of gas on said diaphragm.
36. The combination in a storage water heater system of a reservoir for the water, a gas burner for heating the same, means for cutting off the flow of gas to said burner including a vertically movable main valve movable by gravity in one direction and by gas pressure in the opposite direction, a horizontally disposed seat therefor, means responsive to the changes in temperature of the water in said reservoir for controlling the action of said gas operated means in one direction, a pilot for lighting the said burner and means responsive to the pilot for causing the said gas operated means to close said main valve when said pilot becomes ineffective.
37. In a heating device, a main gas burner for heating water in a reservoir, a valve 20 controlling the flow of gas to the main burner, a device actuated by gas pressure for operating said valve, a thermostat actuated by heat of the water in said reservoir, a valve actuated by said thermostat to open 25 and close and by so acting to thereby control the gas pressure actuated device for operating said main valve, a pilot for the main burner, a thermostat actuated by the heat of the pilot, a valve actuated by said pilot 30 actuated thermostat to open and close and by so acting to thereby control the gas pressure actuated device for operating said main valve.

HENRY E. REEVE.
